We claim the ornamental design for a powered irrigator for sinus cavity rinse, substantially as shown and described.

DESCRIPTION

See application file for complete search history.

FIG. 1 is a front isometric view of a powered irrigator for sinus cavity rinse.

FIG. 2 is a left elevation view of the powered irrigator for sinus cavity rinse of FIG. 1.

FIG. 3 is a right elevation view of the powered irrigator for sinus cavity rinse of FIG. 1.

FIG. 4 is a rear elevation view of the powered irrigator for sinus cavity rinse of FIG. 1; and,

FIG. 5 is a front elevation view of the powered irrigator for sinus cavity rinse of FIG. 1.

The broken lines shown in the figures that are immediately adjacent to the shaded areas represent the bounds of the claimed design while all other broken lines represent environmental structure and are for illustrative purposes only; the broken lines form no part of the claimed design.
